HACK SAW

Carl-Arne Breger, Malmo, and P. Mats A. Danielsson,
Sandviken, Sweden, assignors to Sandvik Aktiebolag,
Sandviken, Sweden

Filed Apr. 8, 1975, Ser. No. 566,053

Term of patent 14 years

Int. Cl. D8—03

FIG. 1 is a perspective view of a hack saw;
FIG. 2 is a side elevational view of the hack saw
shown in FIG. 1;

FIG. 3 is a top plan view; and

FIG. 4 is an end view of the hack saw as seen from the
handle end of the saw.

We claim:

The ornamental design for a hack saw, as shown and
described.
